FOLDING UMBRELLA

Joseph Buono, Jamaica, N. Y.

Application August 26, 1949, Serial No. 112,456

9 Claims. (Cl. 135—46)

1

This invention relates to folding or collapsible umbrellas, and particularly to the type in which the umbrella stick is composed of two telescopic sections, and the ribs are foldable, to thereby reduce the size of the umbrella and enable it to be conveniently carried.

An object of the invention is to provide improved and simplified means by which the telescopic relationship and adjustment of the two sections of the stick may be easily and conveniently had, and by a simplified means unlikely to get out of order and be well able to withstand the uses and abuse to which an article of this character is likely to be subjected.

Another object of the invention is to provide an improved detent means for positioning an inner slidable rod, forming a part of the umbrella stick, at a plurality of definite positions, thereby holding the rod in an extended position, in a position in which it is completely housed in the outer tube of the stick and in a position to enable it to engage the ribs in either folded or open position to thereby hold the umbrella either closed or folded and closed.

Still another object of the invention is to provide a detent member in the form of a single, continuous, lengthy spring wire member of great strength and flexibility, said member by its engagement with the rod, while the same is in one or the other of its telescoping positions with respect to the outer tube, securely and positively engaging said rod and retaining it in the desired positions in which it may be located by the umbrella user.

These and other objects are attained by the invention, a more particular description of which will hereinafter appear and be set forth in the claims appended hereto.

In the accompanying drawings, wherein an illustrative embodiment of the invention is disclosed, Fig. 1 is an elevational view of the umbrella stick and associated parts, some parts being shown in section and others broken away to disclose construction; Fig. 2 is a vertical sectional view of a portion of the stick, showing the rod fully telescoped within the outer tube; Fig. 3 is a front elevation of the outer tube with the spring removed; Fig. 4 is a vertical sectional view through the outer tube, showing the spring in place therein; Fig. 5 is a vertical sectional view through the rod, with the knob thereon shown in section; Fig. 6 shows the relative positions of the parts of the stick when the rod is in its fully extended position, and Fig. 7 shows the relative positions of the parts when the rod is

fully extended and the outer tube is partially telescoped within the inner tube.

Under the drawings, the following description of the invention will be understood:

Referring to the drawings, Fig. 1 shows the umbrella stick 1, which is composed of an outer tube 2 and an inner tube 3, the tube 2 being partially telescoped within the tube 3.

The tube 2 is provided with a knob 4 at its upper end, and a slot 18 is formed in the side wall of the tube 2 adjacent to the upper end.

The tube 3 is provided with a slot 20 in its side wall, and a slot 22 is formed in the side wall of the tube 2 opposite to that side of the wall in which the upper slot 18 is formed.

The tube 2 is provided with an annular stop or collar 5 near its upper end, and a tubular runner 6 is provided with an annular stop or collar 7 near its lower end, the runner 6 being provided with a retaining ring 8.

The tube 2 is provided with a rib brace 9, which is pivotally attached at 10 to a clip 11, which is pivotally attached at 12 to a sleeve 13.

The tube 2 is provided with a rib brace 11, which is pivotally attached at 12 to a sleeve 13, which is frictionally or otherwise fitted at 14 to the tube 2, and is threaded at 15 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

The tube 2 is provided with a rib brace 11, which is pivotally attached at 16 to an outer rib part 15, and is threaded at 14 to receive a tip 16.

2

telescoped within the tube to an extent necessary to cause the knob to engage and retain the tip ends of the ribs of the umbrella.

Referring to the drawings, 1 indicates generally, the stick of the umbrella, the same consisting of three main elements, namely, an outer tube 2 constituting the upper portion of the stick, an inner tubular rod 3 forming the lower end portion of the stick, and the spring or detent member 4 normally housed within and covered by the tube 2 and most clearly seen in Fig. 4.

Near its upper end, the tube 2 is provided with an annular stop or collar 5 to limit the upward sliding movement of the tubular runner 6, the latter being of known construction. Said runner is provided with the retaining ring 7 to which one end of the rib braces 8 are attached. The opposite ends of the rib braces 8 are each pivotally attached at 9 to the clip 10 secured on the rib

11 which is pivotally attached at one end to the ring 12 secured to a sleeve 13 which is frictionally or otherwise fitted at the top part of the tube 2 and is threaded at 14 to threadably receive a tip of conventional form, not shown. The portion of the rib indicated at 11 in Fig. 1 is the inner section of the rib, said part being pivotally attached at 16 to an outer rib part 15 as indicated in dotted lines in Fig. 2. This is not shown in detail since it is well known construction and is widely used in collapsible or foldable umbrellas.

Located within the outer tube 2 and carried by the same is the spring or detent member 4. The member 4 consists of a lengthy section of so-called "piano wire." It is thus of extreme springiness and flexibility. Provided at one end, or that located at the upper end of the stick 1, is a lateral or offset portion 17 on the spring 4 which projects through a slot 18 formed in the side wall of the body of the tube 2 adjacent to the upper end of the tube. On the spring 4 at a relatively short distance below said offset end 17 is formed an outwardly-distorted part 19 constituting a detent or catch for the runner, and which projects through a slot 20 formed in the side wall of the tube 2 opposite to that side of the wall in which the upper slot 18 is formed. Near its lower end, the spring 4 is formed with an outwardly distorted part 21 constituting a detent protruding through a slot 22 in the side wall of the tube 2 and located directly below and in vertical alignment with the upper slot 18.

The shape and formation of the spring 4 is such that when the same is placed within the tube 2 it is under flexure or tension and its tendency is to force the detents 19 and 21 out through their

slots 20 and 22, and to also urge the offset end 17 out of the slot 18. The normal position of the spring 4 when in place in the tube 2 is that shown in Fig. 4.

The inner tubular rod 3 is most clearly seen in Fig. 5, wherein it will be noted that the same threadably receives the knob or handle 23 at one end. At its other or upper end it is provided with a downwardly-extending notch 24 intended for engagement with the detent portion 21 of the spring 4 when the rod 3 is pulled out of the tube 2 to the limit of separation of the rod and tube, or as shown in Fig. 6. It will be noted that directly below the inner end of the notch is provided an outwardly-extending annular bead or rib 25, which, when brought into contact with an annular inwardly directed rib 26 near the lower end of the tube 2, limits the extent of outward movement of the rod 3 from within the tube 2. It is to be further noted that when the notch 24 engages the detent portion 21 of the spring, such engagement of these parts prevents rotative movement of the rod 3 within the tube 2, which is desirable, particularly when the parts of the stick are in the extended position above described.

Relatively near to its lower end, the rod 3 is formed with grooves 27 and 28 resulting in the production of inwardly-extending stop-ribs within the rod for a purpose to be described.

When the umbrella is in its open position, or when the rod 3 is drawn to its limit outward of the tube 2, the parts are in the positions shown in Figs. 1 and 6. That is to say, the rod 3 has been drawn out of the tube 2 until the bead 25 has come into contact with the stop rib 26, and the notch 24 is in engagement with the detent portion 21. The runner 6 has been manually slid along the stick to its elevated position until the upper end of the runner has come into contact with the collar 5, at which time a slot 30 formed in the lower portion of the runner is brought into engagement with the detent portion 19 of the spring 4. The tendency of the runner is to exert a downward force upon the detent portion 19, and since the spring may be forced downwardly due to its retaining end 17 being located in the elongated slot 18, this force is transmitted to the lower end portion of the spring 4, holding the detent 21 thereat resiliently in engagement with the notch 24, thus taking up any looseness or play at this point and maintaining the two sections 2 and 3 of the stick together as a rigid unitary structure.

When it is desired to close the umbrella, the detent 19 is pressed inwardly by the finger so that the runner 6 may be slid downwardly along the stick in the known manner until the same rides over the detent 21 and the slot 30 of the runner engages the latter detent. As the runner slides over the detent 21 it forces the same inwardly, thus freeing it from its engagement with the notch 24 in the end of the rod 3. At this time, a manual pressure imposed upon the knob or handle 23 will enable the rod to be slid inwardly or telescoped into the tube 2 to an extent desired. If it is desired to maintain the umbrella in a closed position with the ribs extended to full length, the rod is pushed into the tube 2 to the extent indicated in Fig. 7, or until the detent 21 resiliently engages against an inner rib or bead shown at 31 and formed near the upper end of the rod 3 a short distance below the outwardly-formed bead 25. This movement is sufficient to cause the tips of the umbrella ribs to enter into

the cavity 32 provided in the knob or handle 23 and be held against outward spread.

If it is desired to completely collapse the umbrella and maintain it in such position with the ribs folded upon themselves, the rod 3 is then telescoped to a greater extent within the tube 2 by the imposition of sufficient force to cause the rib 31 to slide past the detent 21, the spring 4 now fitting within the rod 3 as the rod slides inwardly within the tube 2. Inward sliding movement of the rod 3 will be halted when the detent 21 reaches the inwardly-extending rib 27. The ribs are then folded closely toward the stick, and then to confine the ends of the folded ribs, shown at 33 in Fig. 2, within the cavity 32 of the handle, the knob or handle 23 is given a slight additional push, which brings the rib 27 past the detent 21 until the second rib, shown at 28 is reached by the detent. At this time, the upper end of the rod 3 has reached the offset end 17 of the spring and the limit of telescoping movement of the rod within the tube 2 has been reached. This position is shown in Fig. 2, wherein it will be noted that the pivot-ends of the ribs have entered the cavity of the knob or handle and are housed therein and the folded ribs are thus held against outward spread.

To extend the stick merely requires the outward pull of the rod 3 to its limit as shown in Fig. 6. If the notch 24 has become misaligned from the detent 21 and does not immediately click into engagement with the same, a slight turning movement of the rod 3 within the tube 2 will at once cause the proper engagement of the detent 21 with the notch. When the stick is thus extended, the runner may be slid upwardly and the umbrella raised and used in the known manner.

It will be noted that with the construction presented, a locking engagement of the rod and tube at the various locations required, maintaining the umbrella in its open, closed, and closed-and-folded positions is attained, and that these results are secured by the use of a single detent member, namely a single, lengthy, highly springy wire, which is capable of great distortion and flexure without breaking or becoming inoperative. The spring is inserted by simply flexing it to an extent to enable it to enter the tube 2 and have its offset end 17 brought into engagement with the slot 18. No other fastening means is required, and the sliding and telescopic movement of the parts 2 and 3 of the stick are smoothly and easily performed.

Having described one embodiment of the invention, it is obvious that the same is not to be restricted thereto, but is broad enough to cover all structures coming within the scope of the annexed claims.

What I claim is:

60 1. A folding umbrella comprising a stick composed of an outer tube and an inner rod, the rod sliding telescopically within the outer tube, the tube being provided with a plurality of spaced slots, a detent member in the form of an elongated spring wire contained within the outer tube and provided with projecting parts entering said slots and protruding laterally of the outer surface of the tube, the rod being hollow and slidable over the spring for the greater portion 65 of the length of the spring, said rod moving said projecting parts from out the slots as the rod is slidably moved over the spring.

2. A folding umbrella including a stick composed of an upper, outer tube, a tubular rod slid- 70 able telescopically within the tube, a detent mem-

ber in the form of an elongated wire spring located within the tube, said spring having an offset end, the tube being provided with a slot in its side wall near the top of the tube for the reception of said offset end, the spring having a pair of laterally distorted parts forming upper and lower detents, the tube having slots through which said detents normally protrude, the upper one of said detents constituting a runner-retaining element for holding the runner in raised position, the lower detent constituting means for engagement with the upper end of the rod when the rod is extended out of the tube, the upper end of the rod being provided with a notch for engagement with the lower detent when the rod is in said extended position.

3. In a folding umbrella as provided for in claim 2, wherein the detent member is maintained within the tube by the engagement of the offset end thereof with the slot in the tube near the upper end of said tube, said slot permitting downward extension of the detent member under pressure of the runner to cause the lower detent to be firmly engaged with the notch in the upper end of the rod.

4. A folding umbrella including a stick composed of an upper, outer tube, a tubular rod slideable telescopically within the tube, a detent member in the form of an elongated wire spring located within the tube, said wire being received in the rod for the greater portion of its length when the rod is telescoped to its limit within the tube, said spring having an offset upper end, the tube being provided with an elongated slot in its side wall near the top of the tube for the reception of said offset end, the spring having a pair of laterally distorted parts forming upper and lower detents, the tube having spaced slots through which said detents normally protrude, the upper one of said detents constituting a runner-retaining element for holding the runner of the umbrella in raised position, the lower detent constituting means for engagement with the upper end of the rod when the rod is extended out of the tube, the upper end of the rod being provided with a notch for engagement with the latter detent when the rod is in said extended position.

5. A folding umbrella including a stick composed of an outer tube and a rod slideable within the same, a spring composed of an elongated bent wire located within the tube, means at one end of the spring for engagement with the tube to hold the spring against displacement but permitting limited longitudinal movement of the same relative to the tube, detent portions formed on the spring, slots in the tube through which said detent portions protrude, and projecting elements on the rod for engagement with at least one of the detents to hold the rod and tube in several different positions of telescopic relationship.

6. A folding umbrella as provided for in claim 5, wherein the means at one end of the spring consists of an offset end part, the tube being provided with a slot through which said offset part extends, one of the detent portions consisting of a runner catch, the second detent portion being adapted to interengage with the end of the rod when the rod is drawn to its fullest extent out of the tube, said end of the rod being formed with a notch for engagement with the latter detent portion.

7. A folding umbrella including a stick com-

posed of an outer tube and an inner rod, said rod being tubular and being slideable within the tube, a spring composed of an elongated section of wire located within the tube, means at the upper end of the spring for engagement with the tube for holding the spring against longitudinal displacement but permitting restricted longitudinal movement of the spring, detent portions provided on the spring, the tube having slots in its side wall through which said detent portions normally protrude, stop elements provided on the rod for engagement with said detent portions to locate the rod at various positions of telescopic relationship with respect to the tube, the rod having a notch provided in its upper end for engagement with one of said detents when the rod is fully extended out of the tube.

8. A folding umbrella including a stick composed of an outer tube and an inner tubular rod, said rod being slideable within the tube, a spring composed of an elongated section of wire located within the tube, a laterally-bent end at the upper end of the spring for engagement with the tube for holding the spring against longitudinal displacement, the tube having a slot for receiving said laterally-bent end, said slot permitting restricted longitudinal movement of the spring, detent portions provided at spaced points on the spring, the tube having a plurality of spaced slots in its side wall through which said detent portions normally protrude, stop elements provided on the rod for engagement with at least one of said detent portions to locate the rod at various positions of telescopic relationship with respect to the tube, the rod having a notch provided in its upper end for engagement with the detent most remote from the bent end when the rod is fully extended out of the tube.

9. In a foldable umbrella, a stick composed of an outer tube and a tubular rod telescopic within the outer tube, an elongated wire spring located within and maintained by the tube, said spring having spaced detent portions, the tube having slots in its side wall through which said detent portions protrude, the spring having a laterally-bent upper end, the tube having a slot near its upper end through which said laterally-bent part of the spring extends, the rod being slideable within the tube to enclose all of the spring except the laterally-bent end portion thereof when the rod is inserted to its limit within the tube, said rod when so inserted causing the detent portions of the spring to be moved out of their slots, the rod being provided in its upper end with a notch for the reception of one of said detents when the rod is fully extended out of the tube, and stop means on the rod for engagement by the latter detent to hold the rod in several positions of telescoped relationship with respect to the tube.
